CARTON

Thomas Latimer Ford, Baltimore, Md., assignor to
 The Bartlett Hayward Company, Baltimore,
 Md., a corporation of Maryland

Application May 31, 1935, Serial No. 24,404

7 Claims. (Cl. 40—7)

This invention pertains to boxes or cartons designed primarily to hold and enclose a plurality of units of merchandise of a fixed size and character, and from which one or more units may be removed, from time to time, the carton being again closed and restored to its position on the shelf from which it was withdrawn.

The main object of the invention is to provide, as a portion of the carton, an element which may be brought into masking position with reference to a numeral appearing on the carton indicating the number of units initially packed in the carton, and at the same time to present a surface upon which may be placed a numeral indicating the number of units remaining within the carton after removal of one or more of such units.

Considering piston rings as the boxed merchandise, it may be said that all boxes are shipped from the factory with the number of rings and the size thereof shown on one face of the box, as for example, $12 \frac{3}{4} + .010 \frac{1}{8}$, and such other matter as may be descriptive of the ring characteristics, as for instance the word "Compression". Such boxes are usually stacked upon shelving, with the ring legend or designation exposed.

Automobiles, as is well known, vary as to the number of cylinders, usually four, six, eight and twelve, and it is an item of considerable expense to box the various ring sizes with the exact number of rings for each model, such procedure requiring different size boxes, distinctive markings thereon, and the further item of packing the rings in the boxes. Hence, it is generally the custom to pack the higher number of rings in each box or carton and for the salesman or jobber to remove the desired number, close the box and return it with the remaining rings to the shelf, the box still showing the original index number, say "12".

Such showing is, of course, misleading and results in confusion and complaints.

The box of the present invention presents a simple and inexpensive expedient whereby the party removing a number of the rings may readily cover the indicia of the total number of rings originally packed in the box, and have a surface upon which may be written, if desired, the number of rings remaining in the box. It is, of course, preferable to indicate the number rather than to merely cover over the original number, but in the broader sense of the invention, the subsequent indication is not absolutely essential.

The invention is illustrated in the annexed drawing, wherein:—

55 Figure 1 is a perspective view of the box or

carton with one end open and the indicia of the number of rings which the box is designed to hold, say "12", exposed upon one side thereof;

Fig. 2, a similar view showing a finger outwardly from one of the box flaps and overlying the numeral "12", or its equivalent, and having its end passed inwardly through a slot or opening in the side of the box or carton;

Fig. 3, a perspective view of a portion of a box or carton showing a slight modification of the means to hold the free end of the flap or a portion thereof when it is turned outwardly over the indicia; and

Fig. 4, a similar view of a further modification.

In Figs. 1 and 2 of the drawing, the enclosing structure is shown in the form of a pasteboard box or carton of the usual type, comprising a bottom 1; a top 2; side walls 3 and 4; main end flaps 5 and 6, and also the side flaps, at one end of the box only, one of which is denoted by 7 and the other of which is present in three sections 8, 9 and 10. These latter sections are formed by slitting the usual side flap, for a purpose which will presently appear.

The carton is made up in the instant case from a single piece of cardboard die cut and bent to form, the lines of bending of the various elements with reference to each other being indented as indicated for instance at 11 throughout the structure, to facilitate and define the lines of flexure of the parts, without breakage.

The box in the drawing is designed to have packed therein say "12" piston rings of a given size, as for instance, $3 \frac{3}{4} + .010 \frac{1}{8}$ —Compression. The legend "12" is imprinted upon the box in line 35 with the intermediate flap section 9 and that portion of the side 4 upon which the number "12" appears is slit upon the horizontal lines 12 and 13 and two vertical lines 14 and 14^a, separated at their proximate ends by a section 14^b, which is an integral portion of the side. This arrangement produces, in effect, a tongue denoted generally by 15, which may be freed from its connection with the box side by breaking the section 14^b.

Upon removal of any number less than twelve of the rings from the box, the vendor or user will turn the flap section 9 outwardly, bending the same upon the indented line 11, breaking the section 14^b with his finger-nail.

The section 9 is made longer than the distance between the vertical line of bend 11 and the cuts 14 and 14^a, which, when broken, form a continuous line and define the outer end of the tongue 15; hence, when this section is turned outwardly and

over upon the box side 4, its end may be projected into the box upon a slight depression of the tongue 15 and interlocked with the side, as best shown in Fig. 2. This will cover the index 5 "12" and if eight rings have been removed, the user will mark the numeral "4" upon the then exposed surface of the flap section 9 so that it will indicate clearly that the box contains four 10 rings and no more. The marking will, of course, 15 be in accordance with the number of units withdrawn from the package and may be readily changed if occasion should require this to be done at a later time, by crossing out or erasing the number, say "4", and substituting the proper number in its place. The presence of the tongue 15 facilitates the introduction of the flap section into the folded position, shown in Fig. 2, over the indicia "12".

Ordinarily, the outside of the box is colored 20 and is, therefore, in contrast with the normal color of the inner face of the blank. It follows, therefore, that when the flap is turned outwardly over the side, there will be a marked contrast 25 between the coloration of the flap and the side, which would, in and of itself, indicate to the vendor or salesman that the contents of the box had been broken.

The inward projection of the flap section 9 is not such as to interfere with the withdrawal of 30 subsequent rings or ring sets, and as a matter of fact, they may be readily removed from the opposite end of the box without disturbing either the tongue or the flap section in the least.

It is manifest that the flap section 9 forms an 35 integral portion of the box as does the tongue 15, and that both may be formed at the same time the blank is stamped or cut out. While it is preferred to use the tongue 15, as it facilitates the ease of projection of the free end of the section 40 9 into locking engagement with the side of the box, it is not essential that the tongue 15 be employed nor that the end flap be slit.

Thus, in Fig. 3, there is shown a portion of a 45 box, the side whereof is formed with a slot so positioned with reference to the end flap 9^a as to readily receive its end when it is turned outwardly and over against the side of the box. The slot in this instance is denoted by 16 and the ends thereof will preferably be enlarged as at 17, which 50 will facilitate the entrance of the end flap. Moreover, the flap is of substantially the full width of the box end, or of a width as is usual in such cartons or boxes as they are produced today.

The slot or opening 16 may be continuous, as 55 shown, or discontinuous, this latter by interrupting its length by an easily broken portion of the box side, the same as 18^b (Fig. 1).

In Fig. 4, a still further modification of the box is shown, in that a single vertical slit as 18 is 60 formed in the side of the box, designed to cooperate with the free end of a flap or flap section 9^a, as will be readily appreciated from the foregoing description.

The term "side", as employed herein and in 65 the claims, denotes any portion of the box, unless by the terminology of the claim, such interpretation is precluded.

So, also, the term "flap" as used is designed to cover any portion which is susceptible of being outturned and secured over indicia, and the invention, therefore, is not to be limited to one in which there are three sections, 8, 9 and 10, constituting one of the end flaps. 5

Other forms will readily suggest themselves and naturally fall within the scope of this invention.

What is claimed is:

1. A box or carton having a flap integral therewith and indicia on a portion of the box adjacent thereto to denote the content of the box, said portion likewise having means to hold the flap over the indicia when the flap is turned outwardly over the same. 15

2. A box or carton having a flap secured to the box at one end thereof and indicia on the side of the box adjacent said flap to denote the content of the box, said side having an opening formed therethrough to receive and hold the end of the flap when the same is turned outwardly over the 20 indicia.

3. A box or carton having a flap and indicia on a portion of the box adjacent thereto to denote the content of the box, said portion likewise having a tongue formed therein, said tongue projecting away from the flap and designed when the flap is turned outwardly over the indicia to permit the ready insertion of the flap in part at least, with the end of such part projecting inwardly beneath the body of the box portion bearing the indicia. 25

4. A box or carton having a flap integral therewith and indicia on a portion of the box adjacent thereto to denote the content of the box, said portion having an elongated opening formed therein and located from the end of the box a distance less than the length of the flap and into which opening the end of the flap may be projected when the same is turned outwardly over the indicia to cover the same. 30

5. A structure as set forth in claim 4, wherein the opening is discontinuous by leaving a portion of the side intact.

6. A box or carton having at least one side flap adapted to be projected across the end of the box, said box having upon its side adjacent the flap indicia denoting the content of the box when packed, and said side likewise having a tongue formed therein extending away from the end of the box, the flap being divided into a plurality of sections, one of which stands in alignment with the tongue in the side of the box and of a length greater than the distance between the end of the box and the end of the tongue so that it, the flap, may be introduced through the opening in the box side at the end of the tongue and positioned, in part at least, inwardly of the inner face of the box side when said flap is turned outwardly the tongue depressed and the end of the flap projected inwardly of the box, whereby the indicia may be covered. 35

7. A structure as set forth in claim 6, wherein the indicia appear upon the tongue. 40

THOMAS LATIMER FORD.
